UNITED STATES PATENT OFFICE.

MARTHINE SMETTE, OF UPHAM, NORTH DAKOTA.

HANGER.

Application filed May 16, 1925. Serial No. 30,798.

This invention relates to certain improvements in hangers and has relation more particularly to a device of this general character especially designed and adapted for use in connection with baby swings, and it is an object of the invention to provide a hanger of this kind which is adapted to be supported by a door casing or the like in a manner eliminating the use of hooks.

10 The invention consists in the details of construction and in the combination and arrangement of the several parts of my improved hanger whereby certain important advantages are attained and the device rendered simpler, less expensive and otherwise more convenient and advantageous for use, as will be hereinafter more fully set forth.

The novel features of my invention will hereinafter be definitely claimed.

20 In order that my invention may be the better understood, I will now proceed to describe the same with reference to the accompanying drawings, wherein:—

Figure 1 is a view in perspective illustrating a hanger constructed in accordance with an embodiment of my invention and in applied position;

25 Figure 2 is a view in side elevation of my improved hanger as herein disclosed, the coacting portion of the door structure being shown in section;

Figure 3 is a view in side elevation of one of the attaching plates as herein set forth;

30 Figure 4 is a fragmentary view in end elevation of the plate as illustrated in Figure 3;

Figure 5 is a sectional view taken substantially on the line 5—5 of Figure 3.

As disclosed in the accompanying drawings, C denotes a door casing arranged at opposite sides of the door opening and defining the same and S denotes a baby swing of any desired design.

40 My improved hanger comprises an elongated strap 1 of desired length and which has freely engaged therewith a member 2 which is adapted to be operatively engaged with the swing S or more particularly a suspending ring 3 carried thereby. The member 2 in the present instance is freely engaged with the strap 1.

45 The extremities of the strap 1 are attached to the plates P which are adapted to be inserted from above between the door casing C and the wall whereby the hanger is effectively maintained in desired applied

position and in a manner to assure the requisite suspension of the swing S. Each of the plates P has one end portion returned to provide thereacross a sleeve or barrel 4 and immediately adjacent to such sleeve or barrel 4 at the central part thereof the plate P is provided with an opening 5 through which the coacting end portion of the strap 1 is directed, said sleeve or barrel 4 providing means whereby cutting of the strap is avoided. The opening 5 is preferably formed by striking from the plate P a tongue 6 of requisite dimensions and configuration, said tongue being bent or folded to have close contact with the sleeve or barrel 4 as is particularly illustrated in Figure 5.

50 The end portion of the plate P remote from the sleeve or barrel 4 is tapered or reduced transversely in order to facilitate the insertion of the plate P between the casing C and the wall.

55 With my improved hanger, the swing S may be readily suspended at various parts of the house without having separate hooks or the like as the plates P may be applied or removed with convenience in accordance with the necessities of practice.

60 From the foregoing description it is thought to be obvious that a hanger constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

65 I claim:—

A hanging device comprising a flat plate 100 constructed of a single piece of metal, one end portion of the plate being insertable between the casing of a wall opening and the wall, the opposite end portion of the plate being return-bent to provide a barrel, a portion of the plate adjacent the returned end portion being cut to provide a tongue, said tongue being bent into contact with the barrel to provide an opening in the plate.

70 In testimony whereof I hereunto affix my signature.

MARTHINE SMETTE.
